(57) **CLAIM**

The ornamental design for a lamp, as shown and described.

DESCRIPTION

FIG. 1 is a top perspective view of a lamp

FIG. 2 is a bottom perspective view of the lamp.

FIG. 3 is a front view of the lamp (rear and side views are the same); and,

FIG. 4 is a top plan view of the lamp (Enlarged).

The broken lines in the drawings depict features of the lamp that form no part of the claimed design.
